UNITED STATES PATENT OFFICE.

CECIL E. BRYAN, OF CHICAGO, ILLINOIS.

COFFIN-ELEVATOR FOR MAUSOLEUMS.

1,273,143.

Specification of Letters Patent. Patented July 23, 1918.

Application filed November 20, 1916. Serial No. 132,468.

To all whom it may concern:

Be it known that I, CECIL E. BRYAN, a citizen of the United States, residing at Chicago, in the county of Cook and State of Illinois, have invented certain new and useful Improvements in Coffin-Elevators for Mausoleums, of which the following is a specification.

In modern mausoleums of the type commonly known as "community mausoleums," containing a large number of crypts, these crypts are arranged in tiers, so that it is desirable to have some means for conveniently elevating the coffins which are to be inserted in the upper crypts. On account of the expense of construction and nature of these devices, they are ordinarily not provided with any extra or storage rooms. However, until all of the crypts have become filled, they may be utilized for storage purposes for such devices or equipment as may be inserted therein. These crypts are comparatively small, so that they are not adapted to receive a complete elevating apparatus.

In accordance with the present invention, I provide an elevating apparatus which may be readily knocked down or taken apart, so that it can be stored in one of such crypts.

The objects of this invention are to provide a simple and efficient coffin elevator for mausoleums, which may be readily taken apart so that it may be stored in a comparatively small space, and may again be readily assembled for use; to provide an improved form of elevator for lifting coffins or the like; and in general, to provide such an improved structure or apparatus as will be more fully described hereinafter.

In the accompanying drawings illustrating this invention;

Figure 1 is a side view of my improved apparatus;

Fig. 2 is a plan view of the same;

Fig. 3 is an end view; and

Figs. 4, 5 and 6 illustrate details of construction.

While an elevator of a knock-down type or folding construction such as contemplated by my invention, may be made in various ways, yet these drawings illustrate a preferred construction of the same.

As illustrated in these drawings, the side or base frames 7 and 8 are made comparatively low and of unitary structures. These frames are preferably made of pipes or tubing in the manner illustrated, and are mounted on wheels or casters 9. The cor-

ner brackets or members 10, for securing the pipes together, are made in the form of T's or L's, with inwardly extending projections 11 for engagement with the cross pipes 12, which provide means for securing the frames 7 and 8 together to make a substantial base or truck-like structure. The projections 11 are preferably provided with pins 13 for engagement with slots 14, so as to make bayonet joints between the brackets and cross pipes. The lower brackets 10 may be provided with integrally formed forks 15 for receiving the wheels 9.

The brackets 10 are also provided with upwardly extending projections 16, for engagement with the vertical tubular posts 17, these projections and posts also being provided with pins and slots respectively, for forming bayonet joints, so that the parts may be securely locked together. The upper ends of the posts 17 engage with brackets or connections 18, similar bayonet joints also being provided for making these connections.

The brackets 18 are preferably secured rigidly to the ends of longitudinal tubular bars or pipes 19, and have bayonet joint connections with transverse end bars 20, the whole going to make up a substantial framework for the elevator.

The coffin or casket is mounted on a vertically movable carriage 21, which consists of a light framework provided with rollers 22, so that the coffin may be readily moved longitudinally thereof. This carriage is made sufficiently narrow and of such length that it may be readily inserted in one of the crypts without being taken apart. This carriage may be raised and lowered in any convenient manner, as by means of cables 23, which are provided at their ends with suitable hooks or eyes 24 for attaching the same to the carriage 21 in a manner so that they may be readily detached. These cables pass up over guide sheaves 25, mounted on shafts 26, having their bearings 27 secured to the top members 19. They then pass down and under guide sheaves 28, on shafts 29, having their bearings 30 secured to the top longitudinal members of the frames 7 and 8, and thence to a winding drum 31 mounted on a shaft 32, having its bearings 33 secured to the top members of the frames 7 and 8.

The shaft 33 is provided with a gear 34, which is engaged by a pinion 35 on a stub shaft 36, mounted in a bearing 37. The shaft 36 is provided with a crank 38, for

turning the same, and with a locking pawl 39 for locking the pinion in adjusted position.

When the parts are assembled in the manner shown in the drawings, the carriage or platform 21 may be lowered until it rests on the cross members 12, and the elevator is positioned in front of the crypt in which the coffin or casket is to be placed. The latter is then put in position on the carriage, 10 and by turning the crank 38, the cables are wound up until the carriage 21 is lifted to the proper height, and the coffin may then be slid or rolled off into the crypt. The carriage 21 may then be lowered to its original position, and if the device is not intended to be used again in a short time, it may be taken apart and stored away in one of the crypts. This is conveniently done by taking out the cross members, which permits the side members to be moved apart 15 sufficiently to allow the shafts 26, 29 and 32 to be drawn out of their bearings, so that these shafts, with the parts carried thereby, may be readily packed away. The cables having been disconnected from the carriage 21, they may be wound up on the drum for 20 convenient disposal. The vertical members 17 and cross members 19 are next disconnected and these members, together with 25 the frames 7 and 8 and the carriage 21, may then be easily stored away.

It will be understood that frequently these elevators will not be needed except at comparatively long intervals, and as apparatus of this character is not especially pleasing to look at, and does not enhance the interior view of the mausoleum, my improved arrangement whereby the entire device may be stored away is a particularly 40 advantageous one. The elevator may be removed from storage and set up in a comparatively short time whenever it is necessary to use the same.

In the modified form of construction illustrated in Fig. 6, the cross shafts for the guides sheaves are dispensed with, and bearings 40 are secured to the longitudinal members. These bearings may be made in any suitable form, and are provided with shafts 50 or pintles 41 for the guide sheaves 42. With this arrangement, the cables may be slipped off from the sheaves, the parts disassembled, and the sheaves remain fixed to the longitudinal members, so that the necessity of 55 inserting and removing the cross shafts is avoided.

Having thus described my invention, which, however, I do not wish to limit to the exact arrangement or construction herein shown and described, except as specified in the following claims, what I claim and desire to secure by Letters Patent is:

1. In a coffin elevator for mausoleums, the

combination of a pair of side frames, detachable connections between said frames, 65 detachable posts extending upwardly from said frames, detachable cross members between the tops of said posts, a vertically movable carriage for receiving the coffin rollers on said carriage whereby the coffin 70 may be moved longitudinally thereof, and elevating mechanism co-acting with said frame and carriage for elevating the carriage, the arrangement being such that the parts may be readily disassembled and 75 packed together in a comparatively small space.

2. In an elevator of the class described, the combination of two side frames, wheels for supporting said frames, detachable 80 transverse connections between said frames, detachable posts extending upwardly from the ends of said frames, detachable longitudinal members connecting the tops of said posts, detachable transverse members also 85 connecting the tops of said posts, a vertically movable carriage, rollers on said carriage for supporting the coffin, a winding drum mounted on said frames, means for turning said drum, cables connected with 90 said drum and with the carriage, for raising the latter, guide sheaves mounted on said frames, and other guide sheaves mounted on said longitudinal top members, for 95 guiding said cables.

3. In an elevator of the character set forth, the combination of two relatively low side frames, detachable cross members for connecting said side frames, detachable posts extending upwardly from the ends of 100 said frames, longitudinal connections between the tops of said posts, a vertically movable platform adapted to rest on said cross members when in lowered position, guide rollers on said platform, a winding 105 drum mounted on said frames, means for turning said drum, a plurality of cables connected with said drum and adapted to be wound upon the same, said cables having their outer ends provided with means for 110 connecting with the movable platform, brackets on said frames and on said longitudinal top connecting members, guide sheaves mounted on said brackets, each of said cables being adapted to be rove from 115 the winding drum under one of the sheaves of the frame, and up and over one of the sheaves on the top member, and down to the platform, the arrangement being such that when the drum is turned, the platform will 120 be raised or lowered, and also such that the parts may be readily disassembled for storage.

CECIL E. BRYAN.
